(57) **CLAIM**

The ornamental design for a pet water dispenser, as shown and described.

DESCRIPTION

FIG. 1 is a top perspective view of a pet water dispenser design showing my new design.

FIG. 2 is a front view of a pet water dispenser.

FIG. 3 is a rear view of a pet water dispenser.

FIG. 4 is a left side view of a pet water dispenser.

FIG. 5 is a right side view of a pet water dispenser.

FIG. 6 is a top view of a pet water dispenser.

FIG. 7 is a bottom view of a pet water dispenser, and,

FIG. 8 is a bottom perspective view of a pet water dispenser. Any shading and cross-hatching are not features of the design but are utilized to illustrate the surface contours of the pet water dispenser design in the drawings.

The broken lines depict portions of the pet water dispenser that form no part of the claimed design.
